UNITED STATES PATENT OFFICE.

JOHN E. BOYCE, OF NEW YORK, N. Y., ASSIGNOR TO OTIS ELEVATOR COMPANY, OF JERSEY CITY, NEW JERSEY, A CORPORATION OF NEW JERSEY.

CONTROLLING DEVICE FOR HYDRAULIC ELEVATORS.

1,152,481.

Specification of Letters Patent.

Patented Sept. 7, 1915.

Application filed September 13, 1911. Serial No. 649,150.

To all whom it may concern:

Be it known that I, JOHN E. BOYCE, a citizen of the United States, residing in New York, in the county of New York and 5 State of New York, have invented a new and useful Improvement in Controlling Devices for Hydraulic Elevators, of which the following is a specification.

My invention relates to means for controlling the starting and stopping of elevators or other hoisting apparatus, and is particularly adapted to the control of automatically operated hydraulic elevators.

This application involves subject matter 10 also disclosed in my co-pending application Serial No. 560,474, filed May 10, 1910, for improvements in master machines for controlling hydraulic elevators.

In automatically operated hydraulic elevators it is customary to employ a floor controller or selective device geared to the elevator car or other moving part of the hoisting machinery which operates in unison with the car, and to provide in conjunction 20 with the floor controller an electric push button system, whereby, whenever a push button in the car or at any of the floor landings is operated, the valve which controls the flow of fluid to and from the hoisting cylinder will be automatically operated at a predetermined point in the travel of the car, in order to bring the car to rest at the corresponding floor landing. In this operation it is necessary to commence the movement of the valve before the car reaches the floor landing at which it is desired to stop. The distance, however, through which the car travels in being brought to rest, when the valve is operated at a given speed, varies 25 with the load and speed of the car, so that with the controlling apparatus usually employed it is impossible to bring the car uniformly to rest at the desired floor landing with the varying conditions of load and speed of the car found in actual practice.

An object of the invention is to overcome this defect and bring the car uniformly to rest at any desired floor landing, irrespective of load conditions and speed of the car

at the commencement of operation of the 50 valve. This object I attain by providing means for operating the valve at a speed proportional to that of the car.

Other objects of the invention, and the exact nature thereof, will appear herein- 55 after.

In the accompanying drawings, which illustrate a construction embodying the present invention, Figure 1 is a diagrammatic illustration of a plunger hydraulic elevator 60 system showing the electrical circuits; Fig. 2 is a side elevation of the valve operating device; Fig. 3 shows in part section a modification of the cable clamping device shown in Fig. 1. 65

While the invention is herein shown as applied to an automatic push button plunger elevator having a direct current system of electrical circuits, the same is equally well adapted to elevators other than plunger elevators and for use with a system of electrical circuits employing alternating current.

Referring to the drawings, in which like reference characters denote similar parts, C designates an elevator car carried upon a 75 plunger G adapted to travel in the plunger cylinder B.

V designates a controlling valve which admits water to, or exhausts water from, the plunger cylinder B. 80

P and E designate the supply and exhaust pipes respectively, while K is the to-and-from pipe connecting the valve to the plunger cylinder. A valve stem J passes through a stuffing box 44 at the top of the valve and is provided with rack teeth which mesh with a gear I connected to a sheave H. A counterweight 45 is connected through the cables 46 to the top of the car and serves to counterbalance a portion of the combined weight of the car and plunger. In order to cause the car to ascend the sheave H is rotated in a clockwise direction so as to move the valve stem downwardly and thereby allowing water under pressure to 95 pass from the pipe P through the valve V and into the cylinder B and thus effect an upward movement of the plunger and con-

nnected car. A reverse movement of the sheave H will connect the plunger cylinder with the exhaust pipe E whereupon the preponderance of weight of the car and plunger over the counterweight will force the valve out of the cylinder and permit the car to descend. An intermediate position of the valve closes all communication with the cylinder and the car remains stationary, the plunger resting on the confined column of water in the cylinder.

F designates a floor controller which is connected to operate in synchronism with the elevator car. This connection comprises a running cable L one end of which is secured to the top of the car and passes up over a pair of direction pulleys 40 secured to the overhead beams T from whence it leads down and around a guide pulley 40' and a sheave 41 carried on the floor controller, from here the cable leads over a pulley 40" and is finally secured to the bottom of the car. The sheave 41 on the floor controller is connected through a train of reducing gearing to the shaft 42 upon which are mounted a number of arms 43 which are adapted to open and close certain electric circuits to effect the stopping of the car, at any predetermined floor landing.

47 designates a cable drum about which are wound a pair of cables X and O. The cable X is arranged to operate the sheave H of the valve while the cable O is a standing cable and leads up over a guide sheave R located at the top of the hatchway. Both of these cables are secured to the drum in a well known way so that there can be no slipping thereon. The drum 47 is arranged to be driven by a small electric motor M through a train of gearing 48 (see Fig. 2). The drum and gear train are carried upon a pair of standards 51, 51, while the motor is secured to a sub-base 49, all of which are mounted upon a substantial bed plate 50.

45 A magnetic clutch device A is carried upon the car and is adapted to coöperate with the cable O. This clutch device comprises a lever 52 pivoted at 53 and adapted to engage and grip the cable O, the face of the lever being provided with teeth adjacent thereto. A toothed plate 57 lies on the other side of the cable in close proximity thereto and is carried upon the frame work of the clutch device A. The lever 52 is normally pressed against the cable by means of a compression spring 58 which acts through a rod 59 which carries a head 60 bearing against the lever 52. The lower end of this lever is provided with a slot 56 adapted to receive a pin carried upon the end of a rod 55 which is secured to the magnet core of a magnet 54. It is readily seen that the spring 58 will tend to clamp the cable between the teeth of the lever 52 and plate 57, and any movement of the car when the cable

is thus gripped will produce a corresponding movement of the cable. The magnet 54 is adapted to release the clutch device from the cable and it operates when energized by an electric current to pull the rod 55 in a left hand direction, thereby rocking the lever 52 about its pivot 53 and permitting the car to travel in either direction without imparting any motion to the cable O. Since the latter is connected to the drum 75 47 it follows that any movement of the cable will effect a movement of the valve V through the cable X and thus the movement of the car may be used to move the valve to closed position. The motor M furnishes 80 an additional means for operating the valve since the same will drive the drum in a predetermined direction to effect a movement of the valve to start the car either up or down.

I will now describe the electrical apparatus shown in Fig. 1 and then point out the operation of the system as a whole.

U and D designate, respectively, the up and down starting and reversing switches which control the operation of the motor 90 M to effect the movement of the valve. These switches each comprises a solenoid magnet winding adapted when energized to raise a core and connected contact disk 12 so as to bridge a number of fixed contacts such as 9, 10, 11, the disk normally bridging the fixed contacts 13 and 14 whenever the solenoid is deenergized. The floor controller F comprises a number of fixed contacts such as 20, 21, 23, etc., arranged in pairs, each 100 pair being provided with a bridging contact such as 22, the latter arranged to be moved into and out of electrical engagement with their corresponding contacts such as 20, 21, by the operation of the elevator car. 105

1, 2 and 3, designate the floor relays there being in every instance the same number of these relays as there are floors, which in the present case is three.

7 is the safety car magnet the operation 110 of which insures that after a push button in the car has been operated and the car has arrived at the designated floor landing, the landing door must be first opened and then closed before the car can be started away from the landing. The double wound magnet 5 and 6 is for the purpose of preventing interference between the push buttons. 115

a, b and c designate the floor landing buttons, and a', b' and c' designate the car buttons, while 29, 30 and 31 are the door contacts associated with each floor landing door, the object of these contacts being to insure that all of the doors are in closed position before the car can be operated. 120 125

S designates the field winding of the motor M, while 18 and 19 are resistances connected in series and parallel, respectively, with the motor armature so as to regulate the power of the motor. The supply of cur- 130

rent to the system is designated in the usual manner by the positive and negative signs + and - respectively.

The operation of the system is best shown by pressing one of the push buttons and then following out the circuits, and in carrying out this idea we will assume that the landing button *c* at the top floor is pushed, the car being at rest at the second floor as shown.

5 A circuit may now be traced from the + main through the door contacts 31, 30 and 29, thence by wire 28 through the magnet windings 5 and 6, which latter by the way are wound in opposition to each other, through the contacts 4 and by the wire 32 to the push button *c*. This button being closed the circuit continues by the wire 33 through the winding of the floor relay 3 through the floor controller contacts 20, 22 and 21, and 10 through the winding of the reversing switch *U* to the - main. The energization of the relay 3 will cause the contact 23 to move up into electrical engagement with the magnet core to which one terminal of the magnet of the relay is grounded and this operation will 15 establish a self holding circuit around the winding 6, contacts 4 and the push buttons *a*, *b* and *c*. The current in the winding 6 is now reduced to a very small amount owing to the parallel circuit closed around it by the relay 3 hence the magnet 5 is enabled to overcome the magnet 6 and open the contacts 4 thereby open circuiting the common wire 32 of the floor buttons and rendering 20 these buttons dead or inoperative. The energization of the magnet of the reversing switch *U* causes the contact disk 12 to bridge the contacts 9, 10 and 11 and thereby establish a circuit to the motor *M*. This circuit 25 may be traced as follows: from the + main to the contact 9 and 11, resistance 18, armature brush 16 to brush 17, contact 13', contact disk 15 and contact 14' which latter is connected to the - main. The field *S* of 30 the motor is connected across the line at the contact 10 of the reversing switch. The motor will now start and the drum 47 will be rotated in a direction to open the main valve to cause the car to ascend. It will be noticed that the resistance 18 is always in series with the motor armature, while the resistance 19 is connected across the armature brushes, therefore the motor will run at 35 moderate speed and power, these resistances being of such an amount as to limit the power and speed of the motor to the desired degree. The magnet winding 35 of the clutch device *A* is energized concurrently with that of the motor, it being connected in parallel with the motor field and across the line, therefore the cable *O* is released and becomes free to move as the drum 47 is rotated by the motor. A pair of contacts 38 associated with the clutch device *A* 40 are arranged to be opened by the movement of the clutch, the object of these contacts being to insert a resistance 39 into the circuit of the magnet winding 35 after the latter has done its work so as to economize current. The elevator car will now move upwardly at full speed, the main valve being moved to its fullest extent and the motor while still receiving current being at rest. As the car approaches the designated stopping place which in the present instance is 45 at the top floor corresponding to the push button *c*, the floor controller will operate to move the contact plate 22 out of engagement with the contacts 20 and 21, thereby open circuiting the magnet windings of the 50 floor relay 3 and the reversing switch *U*. The effect of this will be to deenergize the reversing switch and permit the contact disk 12 to open the motor circuit, and at the same time to deenergize the clutch magnet 35, 55 thereby allowing the spring 58 to operate the clutch to grip the standing cable *O*. As the car continues to move upwardly, the cable *O* moves along with it at the same rate of speed, and the latter causes the drum 47 together with the motor *M* to be rotated backward, thereby effecting the closing of the main valve to stop the car, the valve in every instance being closed at a speed proportional to that of the car. The valve being controlled by the movement of the car has an additional valuable function in controlling or preventing creeping of the car. The valve sometimes leaks and permits water to 60 get into the plunger cylinder after the valve is closed, and causes the car to creep upward, or the water may leak out through the valve and thus permit the car to settle. Now since the valve is operatively connected to the car any movement of the latter will cause a corresponding movement of the valve in one direction or the other to admit or exhaust water from the cylinder and thereby compensate for any leakage that 65 may occur.

The operation of the device with a descending car is similar to that already described, the reversing switch *D* however being energized in this case, the floor controller automatically opening the operating circuit at the proper time to permit the clutch device to close the main valve to stop the car at the predetermined floor landing. If the system be operated from the car buttons the circuit differs somewhat 70 from that established by pushing one of the floor buttons. To illustrate, we will assume the car to be at rest at the second floor landing as shown in Fig. 1 and the button *c* in the car to be operated. As before, the circuit may be traced from the + main through the door contacts 31, 30 and 29, magnet winding 5, winding of relay 7, wire 37, to and through the button *c* and by wire 38 through the floor relay 3, floor controller 75

135

contacts 20 and 21, reversing switch U, and to the — main. The contacts 4 immediately open so as to prevent any interference from the floor landing buttons and the relay 7 draws the contact 8 against its core to which one terminal of the winding of the relay is grounded. This operation closes a self holding circuit including the door contacts, winding 5, winding of relay 7 and resistance 27', this circuit being across the line. It will be seen that the floor controller does not interfere with this circuit upon stopping the car by opening the operating circuit at the contacts 20 and 21 and this self holding circuit will remain closed until the landing door has been opened to interrupt it at the door contact, and not until after this has been done can the car be operated from the floor buttons.

20 While I have shown and described the valve as being operated directly through its valve stem, it is to be understood that when the water pressure is high or the valve is of considerable capacity it may be desirable to 25 employ the well known pilot valve mechanism for effecting the movement of the main valve. In that case the cable X would be connected to move the pilot valve through any suitable mechanism. Where no pilot 30 valve is used it is preferable to have the main valve of the balanced type so as to lighten the duty of the motor as much as possible.

Fig. 3 shows in part section a modified 35 form of clutch device A' which comprises a frame 77 surrounding a solenoid 35'. A core 78 is connected to a rod 59' which is adapted to operate a pair of pivoted gripping members 52', 52', through the pin 68 40 and slots 67. The spring 58' is carried upon or surrounds the rod 59' and bears against a collar 70 and nut 71, the latter being for the purpose of regulating the tension of the spring. 72 is an iron plug through which 45 the rod 59' freely passes and is for the purpose of enabling the solenoid to exert a powerful pull while using a magnet of moderate size. The cable O lies between the toothed gripping members 52', 52' and a toothed plate 69, the latter being preferably 50 made of tempered steel and arranged so as to be easily detached or replaced. A sliding member 63 extending through a hole in the lug 64 is adapted to bear against the 55 cable, the end of this member in contact with the cable being somewhat enlarged and provided with a smooth anti-friction face so as to reduce wear on the cable. A spring 65 gently urges this member against the cable, the object being to force the latter away from the toothed plate 69, when the gripping members are swung out of gripping engagement by the energization of the magnet. One of the gripping members is 60 provided with a smooth enlarged portion 66

against which the cable bears when the magnet is energized, the anti-friction members 63 and 66 preventing the cable from sliding against the clutch teeth and thereby wearing out. If desired the members 63 and 66 70 could be provided with anti-friction rollers further to reduce any wear on the cable. A feature of this modified clutch device is the use of two clutch members 52', 52'. By this construction it is seen that when 75 the magnet is deenergized and the spring 58' pulls the clutch members against the cable O the latter is positively gripped and cannot slip, no matter in which direction the car may be traveling, since the greater the pull 80 on the cable the tighter it will be gripped by reason of the wedging action of the members due to their form and the location of their pivot points. Obviously the cables O and X could be replaced by sprocket chains, 85 it being merely necessary to adapt the sheaves H and R and the drum 47 to accommodate the chains instead of cables as shown.

While I have shown the motor as being 90 energized even after the valve has reached its limit of movement, this is not a matter of importance since the motor is of small power and consumes but little current. If desired, however, contacts could be arranged 95 to coat with the valve stem so as to interrupt the motor circuit after the valve has been moved to wide open position, but since this is merely one of many requirements which anyone skilled in the art could readily 100 perceive, I have not considered it necessary to show it.

What I claim is new and desire to have protected by Letters Patent of the United States is:—

1. In an elevator, the combination of a car, hydraulic operating means therefor, a change valve, means for opening the valve, electrically controlled means on the car and having an operating connection with the valve for effecting the closing of said valve, and automatically controlled mechanism for controlling the operation of said valve opening and closing means. 110

2. In a hydraulic elevator, the combination of a plunger and connected car, a plunger cylinder, a valve controlling the movement of said plunger, an electric motor for operating said valve to open position, a standing cable operatively connected to said valve, a magnet controlled clutch on the car for effecting an engagement with said standing cable, and automatically controlled electrical apparatus for effecting the operation of said motor and clutch. 115

3. In an automatic electric control system for push button hydraulic elevators, the combination of a change valve, an electric motor for moving said valve to open position, a cable operatively connected to said 120

valve for moving the latter to closed position, means carried on the car for engaging and disengaging said cable, and a selective device controlled by the movement of the car for effecting the operation of said motor and said cable engaging means.

In testimony whereof, I have signed my

name to this specification in the presence of two subscribing witnesses.
